Patented Nov. 25, 1975

237,811

TOY CATAPULT

Adolph E. Goldfarb, 4614 Monarca Drive, Tarzana, Calif.
91345, and Erwin Benkoe, 17965 Medley Drive,
Encino, Calif. 91316

Filed Feb. 13, 1974, Ser. No. 442,152

Term of patent 14 years

Int. Cl. D21—01
U.S. Cl. D34—15 PP

FIG. 1 is a top plan view of the toy catapult showing our new design;

FIG. 2 is a side elevational view thereof;
FIG. 3 is a front elevational view thereof;
FIG. 4 is a rear elevational view thereof;
FIG. 5 is a bottom plan view thereof; and
FIG. 6 is a perspective view thereof.

We claim:

The ornamental design for a toy catapult, as shown.
